[57] CLAIM

The ornamental design for a shoe outsole, as shown and described.

DESCRIPTION

FIG. 1 is a bottom plan view of a shoe outsole showing our new design;

FIG. 2 is a side elevational view of one side of the shoe outsole shown in FIG. 1;

FIG. 3 is a side elevational view of the other side of the shoe outsole shown in FIG. 1;

FIG. 4 is a rear elevational view of the shoe outsole shown in FIG. 1;

FIG. 5 is a front elevational view of the shoe outsole shown in FIG. 1;

FIG. 6 is a cross section taken along line 6—6 of FIG. 1; and,

FIG. 7 is a cross section taken along line 7—7 of FIG. 1.

The broken line showing of a sole periphery and a shoe upper in FIGS. 2-5 are for illustrative purposes and form no part of the claimed design.

FIG. 1

FIG. 7

FIG. 6

FIG. 5

FIG. 4
